(57) **CLAIM**

The ornamental design for a dual receptacle, as shown and described.

DESCRIPTION

FIG. 1 is a top, right, and front perspective view of a dual receptacle in use condition, showing my new design;
FIG. 2 is a top, right, and front perspective view thereof;
FIG. 3 is a front elevation view thereof;
FIG. 4 is a right side elevation view thereof, the left side elevation is a mirror image of the right side;
FIG. 5 is a top plan view thereof; and,
FIG. 6 is a bottom plan view thereof.

The broken line in the drawing views is included for the purpose of illustrating environment and forms no part of the claimed design.
